UNITED STATES PATENT OFFICE.

ALBERTO TORCHIA, OF BROOKLYN, NEW YORK, ASSIGNOR OF ONE-FOURTH TO JOSEPH BRUNO, OF BROOKLYN, NEW YORK.

AUTOMATIC LETTER-DISTRIBUTING SYSTEM.

Application filed April 22, 1926. Serial No. 103,759.

This invention relates to a new and useful device in the nature of a mail distributor, said device being particularly adapted for use in delivering or distributing mail.

5 The object of the invention is to provide a mail distributor of novel construction and arrangement of parts, hereinafter more fully described, claimed, and illustrated in the accompanying drawing, in which:

10 Fig. 1 is a perspective view showing my improved mail distributor as adapted for delivering or distributing mail to houses, or in rural sections.

Fig. 2 is a sectional view of an office building, showing my improved device installed therein.

15 Fig. 3 is an enlarged perspective view of the car or carrier as used in connection with my improved device.

20 Fig. 4 is an enlarged side elevational view of the control device as used in connection with my improved mail distributor.

As here embodied my improved mail distributor comprises a carrier or car having 25 wheels 10 with flanges to accommodate a track 11, said wheels being rotatively mounted on shafts suitably attached to the supports 12, at their upper extremities; the container 13 being of suitable shape to accommodate a plurality of drawers 14, slidably held 30 therein, is suitably attached to the lower extremities of the supports 12. The drawers 14 being of suitable dimensions to accommodate letters and mail matter, and being numbered consecutively. As a means of driving 35 the heretofore mentioned car, I have provided an electric motor 15, of common construction, attached to one of the supports 12, and having a pulley over which the belt 16 is 40 extended, which is also extended over a pulley attached to one of the wheels 10. It should be understood that the carrier 13 is suspended from the track 11 by two pairs of supports each of which are connected at 45 their lower ends to the carrier. The carrier 13 preferably comprising insulating material such as fibre or wood so that each pair of supports are electrically insulated from each other. The motor 15 is mounted on one support of one pair of supports and is electrically connected with one of the supports of the other pair by a conductor 12'. In this manner current is supplied from one of the rails directly to the motor through the support on which it is mounted and from the

other rail through the conductor connected with a support depending therefrom, it being understood that the said rail 11 is held in place or suitably suspended by means of hangers 17 attached thereto and to any convenient place.

Referring in particular to Figure 4, of the accompanying drawing, as a means of stopping the said car at any desired place on the track 11, I have provided an extending strip 18, suitably attached to one of the supports 12, having a plurality of notches 19, located at the top and bottom, it being understood that the notches 19 will be numbered consecutively and of a suitable number to correspond with the said drawers 14. I have also provided stop rods 20, slidably mounted on a bearing 21, and having attached at one extremity a lever 22, pivoted as at 23, the said lever 22 being attached to the operating rod 20, by means of a slot 24 in the lever 22, and a pin 25 attached to the operating rod 20 engaging in the slot 24. When the switch 26 is closed, electric current from the battery 27, or any suitable source, will cause the electromagnet 28, which is suitably connected to the switch 26 and battery 27 to move the operating rod so as to assume the position designated by the numeral 30, which will stop the said car, it being understood that a plurality of the above mentioned devices are provided to correspond with the number of notches provided.

It has already been stated that each of the notches 19 is numbered in correspondence with the drawers of the carrier and it is the purpose of the stop rods 20 to indicate which particular drawer contains the letters directed to the station at which the carrier is stopped, it being understood that each station may be equipped with the mechanism illustrated in Fig. 4 if desired and that there are as many stops at each station as there are notches in the bar. The rods 20 are of sufficient length to be extended past the ends of the notches 10 so as to engage the bar 18 and prevent the continuation of the carrier. After the mail or letters have been removed at their intended station the bar which has been extended by the magnetic action may be manually retracted against the action of its magnet so as to permit the carrier to travel on to the next station.

It should be understood that each station is provided with a set of magnetically con-

trolled arms 20 and that any one of the arms may be extended in the path of the bar 18. If it is desired to indicate that letters are contained in more than one drawer of the carrier, other bars 20 may be extended magnetically for indicating by means of the numbered notches which other drawers contain letters. In this manner separate mail service may be given to a number of individuals residing near one station.

Referring in particular to Figure 1 of the accompanying drawing, I have shown the track 11 suspended from the hangers 17 attached to the cross arms 31 of the telegraph poles 32, and also to the houses as at 33, although I do not necessarily limit my invention to this particular method of supporting the hangers 17.

Referring in particular to Figure 2 of the accompanying drawing, I have shown the track 11 suspended from the hangers 17 conveniently attached to the walls or in the partition of the building, and suitably placed so as not to interfere with the general accoutrements of the building. It being understood that my improved device may be similarly installed in public buildings, apartment houses and the like, and that the said track 11 may be carried from one floor to another, as clearly shown.

It will be understood that my improved device will be controlled from the post office, or post office sub-station, which ordinarily handles the territory or section, and that two tracks will be provided for the sending and returning of the car as used in connection with my improved device.

While I have above described the preferred form, construction, and arrangement of the several elements employed, it will be understood that the device is, nevertheless,

susceptible of considerable modification therein, and I therefore reserve the privilege of resorting to all such changes as may be fairly embodied within the spirit and scope of the invention as claimed.

Having thus described my invention, what I claim as new and desire to protect by Letters Patent of the United States is as follows:—

A mail distributing system of the class described comprising a pair of overhead tracks, traction wheels mounted on said tracks, supports depending from said wheels, a carrier comprising a plurality of consecutively numbered drawers adapted to contain mail, an electric motor mounted on one of said supports and electrically connected with said tracks through the traction wheels mounted thereon and operatively connected with one of said traction wheels adapted to propel said wheels and said carrier, a contact bar mounted on one of said supports and extended laterally on both sides thereof having a plurality of notches therein numbered consecutively in correspondence with the numbering of said drawers, stopping mechanism mounted adjacent said tracks comprising a plurality of electric magnets each connected independently in series with a source of power, and a plurality of stopping arms each associated with one of said magnets adapted to be projected into the path of said contact bar for engaging the same to stop the travel of said carrier and adapted to indicate which drawer contains mail for that station at which the carrier is stopped by designating a predetermined notch and the number associated therewith.

In testimony whereof I have affixed my signature.

ALBERTO TORCHIA.
